GRAIN DOOR, ITS INSTALLATION AND REMOVAL

Homer S. Sackett and Emmet G. Stack, Portland, Oreg.

Application July 18, 1951, Serial No. 237,376

5 Claims. (Cl. 20—36)

Our invention relates to improvements in the grain doors used in loading grain in box cars and has for its objectives an easier installation and removal of said doors and a minimizing of the damage to said doors common in current practice.

The present day box car used on our railroads is provided with two side doors thru which pass the commodities the car transports. Whenever grain is the commodity the door openings must be partially covered temporarily with what are known to the trade as grain doors so that the space between the two door openings may be utilized.

These so called grain doors are made up in 18" wide sections stacked edgewise one on the other to a depth of four, or six feet. An 18" wide section is made up of random width lumber cut 7'-0" long with the pieces cleated together at each end with a piece of 1" x 6" x 18" long. A second course of lumber cut 6'-0" long is positioned between the cleats and nailed to the first course. Care is taken that the pieces making up the two courses break joints and that knot holes or other defects in one course do not come opposite similar defects in the other course. This construction permits low grade lumber to be used. In practice all four sections of a door are made similar and of like material.

When a car of grain is to be loaded, four door sections are set in place at each car opening and nailed to the jambs thereof or the car sides usually with four to eight 20d spikes per section. The average car is loaded to a depth of six feet or to the top of the grain door.

When the car reaches the elevator, the door sections must be lifted upwardly so that the grain behind them may flow out from under them into the unloading pit. The current practice is to drive a pinch bar under the bottom door section and pry it up. The larger elevators use a hydraulic jack made so that its foot may be driven under the bottom door section as was the pinch bar. Wheat creates a lateral pressure of approximately 297 pounds per lineal foot against a grain door and a vertical pressure of some 125 pounds per lineal foot. The jack must not only overcome the lateral and vertical pressure against the door but in addition must shear the spikes or pull them out of the door sections and/or the jambs or car lining. Such practice is very hard on the door sections and they must be constantly repaired or replaced.

These grain doors are the property of the various railroads. Each year the requested number of door sections are delivered to each grain-loading point. At the elevators a nation-wide organization picks up the door sections and returns them to the railroad's distribution depot where they are repaired if that is possible.

Now that plywood is made up with waterproof resins it is proposed to use this material in lieu of the built-up door section. The door sections will be made 24" wide since two sections may be ripped from the standard 48" wide plywood panel. Only three sections will be required to form the door instead of four as with lumber.

In Fig. 2, of the drawings which accompany this specification is shown that portion of the grain behind the grain door which creates the lateral and vertical pressure thereagainst. It is apparent from Fig. 2, that the maximum pressure against the door is at the floor line and that the lateral pressure against the door varies from nothing at the top to a maximum at the bottom. It is therefore apparent that the door thickness might be varied from top to bottom if it were practicable. It is practicable to a certain extent when plywood is used. 1" fir plywood has approximately the same strength as the

2

built-up door section using two courses of $2\frac{5}{32}$ " boards of 1000# stress material. As a matter of fact $1\frac{3}{16}$ " plywood may be used for the top section, $1\frac{1}{2}$ " plywood for the middle section, and 2" plywood for the bottom section.

5 Such an arrangement saves money, material, and weight. Since plywood panels are made up of from three or seven plies of veneer there is not a chance in a million of aligned defects in all plies.

The make-up of a plywood grain door and its application is set forth in the accompanying drawings in which Fig. 1, is an elevation showing the door sections in place in a car opening; Fig. 2 is a vertical section on the line 2—2 of Fig. 1; Fig. 3 is a full size section showing the application of a formed clip to all three door sections; Fig. 4 shows a straight clip; Fig. 5 is an isometric view of a formed clip; Fig. 6 shows one application of a straight clip; Fig. 7 shows another application of a straight clip; Fig. 8 is a section thru the dado cut in the bottom of the bottom door section for the reception of a pinch bar or jack; Fig. 9 is an enlarged section on the line 9—9 of Fig. 10, thru the pocket formed for the reception of the clips and nails therefor during transit; Fig. 10 is a plan of a door section showing the location of the pocket and dadoes; Fig. 11 shows fragmentary sections of graduated door sections; Fig. 12 is an elevation of a rabbeted door section; Fig. 13 shows a section-securing means with the head concentric with the shank; Fig. 14 shows a section-securing means with a head projecting from one side of the shank.

Throughout the drawings and the specification similar numerals refer to similar parts.

Instead of describing a grain door D having sections of like thickness, one having a section similar to that shown in Fig. 2 will be described. The top section 1 may be of $1\frac{3}{16}$ " fir plywood, the middle section 2 of $1\frac{1}{2}$ " fir plywood, and the bottom section of 2" fir plywood.

Standard commercial plywood panels are made 4'-0" in width and of various lengths with all edges and corners square. It is to be noted in Fig. 2, that the top edge 1A of section 1 and the bottom edge 3A of section 3 are square while the joint J between sections 1 and 2 and 2 and 3 are on a bevel of approximately 2" to the foot with the slope toward the grain side. By tilting the ripsaw to provide the desired slope and ripping a panel on its centerline two top or two bottom door sections may be made at one time. A panel for the middle sections 2 may be ripped in a similar manner but the opposite longitudinal edge of each section must also be bevelled as shown in Fig. 2.

50 The grain doors of lumber, now in use, are all square-edge and it follows that the plywood grain door sections might be left square-edged, or tongue and grooved edges might be used. However, the bevel edge is simple and there is nothing to break off and since the grain exerts so much lateral and vertical pressure against the door sections such pressure has a tendency to close and keep closed the bevel joint.

In order to eliminate the use of spikes to hold the grain door sections in place while a car is being loaded, other means are provided, several forms of which are shown together with their application. Fig. 4 shows a straight clip 4 and Fig. 5 shows a formed clip 5. These clips are preferably made of spring steel which may be had in strip form from $\frac{1}{2}$ " to $\frac{3}{4}$ " in width and from .020" to .035" in thickness. There is a resiliency in spring steel and it has a tendency to resume its original form when forced out of line. This fact has been made use of. For instance, the formed clip 5 shown in Fig. 5, assumes the shape shown in Fig. 3, when in use and exerts in that form considerable pressure on the door sections because of its inherent tendency to resume its original form or that shown in Fig. 5. The straight clip 4 likewise is under tension when applied as in Figs. 6 and 7, and immediately straightens out when out of contact with the door section.

75 Two holes 6 are provided in each clip—either 4 or 5—for the reception of 3d nails 7 which secure the clips to the jamb or car lining 8. Two clips, as 5, are provided at each end of each door section as shown in Fig. 1. Staples (not shown) may be used in lieu of the nails 7.

The straight clip 4 is made about $2\frac{1}{2}$ " long and if it is to be applied as shown in Fig. 6, its end 9 is preferably

rounded off to eliminate corners that might dig into the door sections as they are raised vertically by a jack or pinch bar.

Fig. 6 shows a groove 10 formed in the ends of the door sections preferably the same distance from the car lining 8 regardless of the door section thickness. In other words, the face 10A of the groove 10 is in alignment in all three door sections as they lay against the car lining. If the straight clip 4 is applied as shown in Fig. 7, one end 4A may be bent slightly out of line to form the shoulder 11 which the corner 12 of a plywood door section may engage. The shoulder 11 serves to position the clip 4 as it is fastened to the car jamb or lining 8—some cars have steel jambs and some have wood jambs but all have a wood lining which is usually flush with the jambs. The formed clip 5 is preferably formed with a shoulder 11 and its standard portion 13 is preferably made somewhat shorter than the plywood door section it is to be used with in order to set up a tension in the clip base 14 when in use. In other words a clip standard portion may be made $\frac{1}{4}$ " to $\frac{1}{2}$ " in length which length will work with $1\frac{3}{16}$ " plywood and the bent end 5A may be made about $\frac{1}{4}$ " long as is the end 4A of the straight clip 4.

To prevent further damage to the door section, dadoes 15 have been provided in the bottom edge of the bottom door section 3 for the reception of the pinch bar or jack that may be used to lift the door sections. It is made with a taper sloping toward the grain side. To prevent crushing of the dado the same has been lined with a piece of spring steel 16 which is cut a trifle longer than the dado length and sprung into place. The ends may be serrated—the serrations not being shown—so that the ends 16A may more readily bite into the end of the dado. Fig. 10 shows the approximate desired location of the dadoes 15.

It is current practice to unload each wood door section separately, since if they were bundled four to the door they would weight approximately 225#, a weight not readily handled by one man. The three plywood door sections banded together will weight only 194# a weight more readily handled. By banding the three door sections in one package the bottom section may have a pocket 17 routed out of one face. This pocket 17 may be made wide enough to receive clips 4 and/or deep enough to receive the standard portions 13 as shown in Fig. 9. The nails 7 may also occupy this pocket 17. The clips and nails are prevented from dropping out by the other door sections in the jackage—not shown. When a door is about to be put in position the proper fastenings are always on hand. When the door is to be removed all that is necessary is to push it inwardly since the spring clips 4 and 5 yield readily.

The method disclosed of making, installing, manipulating, and removing grain doors means the saving of many thousands of dollars to the railroads and the holding of many millions of feet of timber for posterity since many of the railroads use as much as 25,000,000 feet of lumber each year for grain door replacement.

It is apparent that the clips may be designed for use with the lumber door sections and it is also apparent that many deviations in them may be made without departing from the basic idea covered in the appended claims, and that means other than the spring steel clips may be used to hold the door sections in edgewise stacked relation and which, like the clips, permit the door sections to be raised vertically and removed without damaging them.

In Fig. 11, fragmentary sections are shown of one end of grain door sections 1, 2, and 3, each formed with a rabbett 18 leaving the portion 19 of uniform thickness and the face 20 of the rabbett 18 in alignment in all sections as was the face 10A of the groove 10. It is apparent that the clips 4 and 5 may be used, whether the ends of the door sections are grooved or rabbeted.

However, Fig. 11, shows a different form of section-securing means 21 which primarily consists of a shank portion 22 and a head portion 23. This head 23 may be

concentric with the shank 22 as shown in Fig. 13, or only project from one side of the shank 22 as shown in Fig. 14. This latter form is shown in Figs. 11 and 12, which show the shank portion 22 driven into the car lining 8, the shank portion 22 being positioned in close juxtaposition to the end of the door sections 1, 2, and 3, with the head 23 overlapping and in close juxtaposition to the face 20 of the rabbett 18. This arrangement keeps the door sections in the edgewise stacked relation yet permits them to be freely moved vertically without damaging the sections.

If this form of door section-securing means is used, the bevelled joint J, the dadoes 15, and the pockets 17, previously discussed are applicable.

It may be remarked at this time that it would not be necessary to rabbett section 1 if the portion 19 is made as thick as said section.

It may also be remarked that the tension set up in the clips 4 and 5 varies with the gauge of the clip stock, the length of the clip base 14, and the thickness of that part of the door section engaged by the shoulder 11.

What we claim as new over the prior art is:

1. A grain door for a box car including a plurality of plywood sections arranged in edgewise stacked relation, the sections being graduated in thickness from the bottom to the top with their adjacent edges bevelled and their ends milled to provide a portion of uniform thickness, and means, secured to the car side, having portions overlapping said uniformly thick end portions of the door sections to hold said door sections in edgewise stacked relation and leave them free to be moved vertically.

2. A grain door, for a box car, having a plurality of sections arranged in edgewise stacked relation, each section being of uniform thickness throughout a major portion of said section with adjacent sections being of different thickness, the section of greatest thickness being positioned in the arrangement adjacent the car floor, and each section having the same end thickness.

3. A grain door, for a box car, having a plurality of sections arranged in edgewise stacked relation, each section being of uniform thickness throughout the major portion of said section with adjacent sections being of different thickness, the section of greatest thickness being positioned in the arrangement adjacent the car floor, said section of greatest thickness having a dado cut in the edge positioned adjacent the car floor for the reception of means whereby the several sections may be raised vertically as a unit.

4. A grain door, for a box car, having in combination, a plurality of sections each section being of uniform thickness throughout a major portion thereof, with adjacent sections being of different thickness, the section of greatest thickness being positioned at the point of greatest stress, and means to hold the several plywood sections in vertical stacked relation against the car side said means having a shank portion adapted to be driven into the car side to bear against the opposite ends of each section and a head portion adapted to lap over the section end portions adjacent thereto said end portions being of the same thickness in all door sections to permit the ends of all door sections to pass under said overlapping head portions when the door sections are raised vertically as a unit.

5. A grain door such as claimed in claim 4, wherein each of the door sections comprise a single sheet of plywood.
